GARRETTSON SMITH AND HENRY BROWN, OF PHILADELPHIA, PENNSYLVANIA, ASSIGNEES
TO SMITH, JOHNSON, AND COMPANY, OF SAME PLACE,

Design No. 2,986, dated March 31, 1868; antedated February 25, 1868.

DESIGN FOR A COOK'S STOVE.

The Schedule referred to in these Letters Patent and making part of the same.

TO ALL WHOM IT MAY CONCERN:

Be it known that we, GARRETTSON SMITH and HENRY BROWN, of Philadelphia, county of Philadelphia, State of Pennsylvania, have invented or produced a new and original Design for a Cooking-Stove; and we do hereby declare that the accompanying drawing, and the following explanation thereof, form a full, clear, and exact description of the said design.

The figure in the drawing represents the stove in perspective, A being the side plate, having a large door and small door ornamented, as clearly shown; B, the upper top plate; C, the upper front plate, having ornaments of a character similar to those on the doors of the side plate; D, the upper top plate; E, the lower front plate, having the two ornamental doors shown; F, the bottom plate, and G the legs.

We claim the design for a stove, substantially as represented in and by the accompanying drawing.

In testimony whereof, we have signed our names to this specification in the presence of two subscribing witnesses.

GARRETTSON SMITH,
HENRY BROWN.
